United States Patent Office.

A. S. KENDALL, OF GUILFORD, MAINE.

Letters Patent No. 73,904, dated January 28, 1868.

IMPROVEMENT IN HORSE-RAKES.

The Schedule referred to in these Letters Patent and making part of the same.

TO ALL WHOM IT MAY CONCERN:

Be it known that I, A. S. KENDALL, of Guilford, in the county of Piscataquis, and State of Maine, have invented a Horse Hay-Gatherer; and I do hereby declare that the following is a full and exact description thereof, reference being had to the accompanying drawings, and to the letters of reference marked thereon.

To enable others skilled in the art to make and use my invention, I will proceed to describe its nature, construction, and operation.

The nature of my invention consists in providing the rake-teeth of a hay-gatherer with an arrangement for lifting the teeth over any obstacle that may be met with; also in constructing a hay-gatherer that, while it is moved forward, the hay collected on the teeth of the machine is drawn or gathered into the receptacle behind.

Drawings.

Figure 1 is a side elevation of my improved hay-gatherer.

Figure 2 is a plan of the same.

Figure 3 is a vertical section.

Figure 4 shows an elevation of one of the teeth, with the rake-point as it appears when meeting with an obstruction.

Figure 5 shows a tooth with the rake-point extended.

Figure 6 shows a vertical section of the collecting and gathering-in arrangement.

A, figs. 1 and 2, represents the body of the gatherer, which is supported upon a single axle, not shown in the drawings. The axle is so arranged that it is free to revolve when it is desirable, or it may remain stationary, and the wheels W W revolve on it. These wheels W W are connected with the axle by means of the toothed couplings D D, figs. 2 and 3. These couplings are operated by the levers E E, connecting-bars F F, and hand-lever G, fig. 3. When it is desirable that the axle should revolve with the wheels, and thus operate the cranks C C, the couplings D D are thrown into gear by the hand-lever G. Attached to the axle at each end are two cranks, C C, that revolve and operate, through the links L L, the sliding frame M, to which the rake-teeth N N, &c., figs. 1, 2, and 6, are attached. P P P, &c., represent the rake-teeth by which the hay is first taken from the ground, and are of a peculiar construction, as represented in figs. 1, 4, 5, and 6. The principal tooth P, has attached to its lower extremity a small secondary tooth, Q, which is capable of sliding longitudinally under its principal, but is usually thrown out by means of the spring R, as shown in fig. 5; but in case it meets with any obstacle, as shown in fig. 4, it is pushed back, which action bulges out the spring R, which, pressing upon the ground, has a tendency to raise up the tooth and let it glide over the obstacle. S, figs. 1, 3, and 6, is a bar upon which rest all of the rake-teeth P, &c. This bar is supported by two hangers, T T, by means of which, and the levers U U, all of the teeth may be raised from the ground. The levers U U are operated by the feet of the driver, who sits on the seat X. The teeth P P swing upon the rod a, fig. 6. The rear end of the hay-receptacle is closed by a swinging door, J, figs. 1 and 2, which is pivoted at b, fig. 1, and is opened or shut by the hand-lever H, acting through the link I. The bottom of the receptacle is closed by a pivoted door, B, which is operated by the bent hand-lever K and the link L'. This bottom door B rests on a small projection on the lower end of the door J, so that the door B drops of its own accord when the door J is opened, and thus the hay gathered into the receptacle by the rake N O, figs. 1 and 6, is deposited.

The machine is operated as follows: In being driven forward the hay is collected upon the teeth P. The hay-gatherer N O is moved backwards and forwards over the teeth P, by the revolution of the wheels acting through the cranks C and links L L, and in this manner gathers all the hay upon the teeth P into the receptacle, which, when filled, may be emptied at any desired place. This operation of discharging the contents of the receptacle is performed by working the lever H, which, opening the door J on the pivot b, releases the bottom door B, which immediately falls and deposits the hay collected.

The principal novelty of my invention consists in the construction of the belts P Q, and applying to a hay-rake or gatherer the hauling-in arrangement M N O, worked as shown and described.

Having thus described my invention, I will now proceed to set forth my claim.

What I claim as my invention, and desire to secure by Letters Patent of the United States, is—

1. The rake-teeth, in combination with the secondary teeth Q and spring R, substantially as described and for the purpose set forth.

2. The rake-teeth P and secondary teeth Q, in combination with the hay-gatherer M N O, operating as set forth, for hauling the hay into the receptacle, substantially as described.

Witnesses:

EDWIN O. COLE,

HENRY S. MANNING.

A. S. KENDALL.
